CLAIM

The ornamental design for a jewelry box, as shown and described.

DESCRIPTION

FIG. 1 is a perspective view of a jewelry box, showing my new design;

FIG. 2 is another perspective view thereof;

FIG. 3 is a front view thereof;

FIG. 4 is a rear view thereof;

FIG. 5 is a left side view thereof;

FIG. 6 is a right side view thereof;

FIG. 7 is a top plan view thereof;

FIG. 8 is a bottom plan view thereof; and,

FIG. 9 is a perspective view in a dosed configuration thereof. The dash-dash broken lines in the drawings depict portions of the jewelry box that form no part of the claimed design.
